UNITED STATES PATENT OFFICE.

THOMAS B. DOOLITTLE, OF BRANFORD, CONNECTICUT, ASSIGNOR TO HARRY W. DOOLITTLE, TRUSTEE, OF NEW HAVEN, CONNECTICUT.

CONTROLLING THE EXHAUST FROM INTERNAL-COMBUSTION ENGINES.

No. 921,679.

Specification of Letters Patent.

Patented May 18, 1909.

Application filed August 27, 1908. Serial No. 450,459.

To all whom it may concern:

Be it known that I, THOMAS B. DOOLITTLE, a citizen of the United States, and a resident of Branford, in the county of New Haven and State of Connecticut, have invented a new and useful Improvement in Controlling the Exhaust from Internal-Combustion Engines, of which the following is a specification.

10 My invention relates to means for handling the exhaust from internal-combustion or explosive engines used in marine propulsion and it has for its object to overcome the noise of such exhaust without interposing any obstacle to its free discharge.

In carrying out my invention I cause the products of explosion discharged from the cylinder and preferably also the water discharge from the cylinder jacket to enter a 20 chamber or chambers communicating with the sea or other body of water in which the vessel is borne. The water in the chamber having free communication with the water outside is of the same temperature, which is therefore 25 much lower than that of the water and gas discharged therein, and in this way it acts to reduce the temperature of the exhaust to a point at which it may be discharged freely without undue expansion 30 and consequently without noise.

In the drawings which accompany and form a part of this application, the figure is a diagrammatic view showing one embodiment of my invention.

35 In the drawings, A represents the cylinder of an explosive engine and B the discharge of the water which has been pumped through the water jacket I.

C represents a chamber communicating 40 with the outside water as shown at F, and hence containing a body of water D at sea level. Into this chamber also as shown at E is introduced the exhaust from the cylinder A. A pipe G, preferably carried through 45 the side of the vessel above the water line, permits free escape from the chamber C. The outer end of the pipe F may be so formed as to cause the water of flotation to be forced into the chamber C by means of 50 the forward motion of the vessel, and thus more rapidly cool the contents of the chamber C. A lip or projection f upon the pipe F may be used for this purpose.

It will be observed that in the apparatus herein shown and described there is no 55 baffle or other obstacle to the discharge and hence there can be no possibility of objectionable back pressure in the cylinder. On the other hand experience has shown that the discharge is wholly or substantially 60 noiseless.

The discharge from the cylinder jacket need not necessarily be led into the chamber C, but may be independently disposed of, but its being carried into said chamber is 65 believed to be both convenient and beneficial.

It is obviously desirable to have the exhaust passage from the engine enter the 70 water chamber C at a point above the water level thereof to avoid back pressure. It is also convenient, although not so essential, to have the passage from the water jacket to the engine enter the chamber C above its 75 water level.

I claim:

1. In a device for preventing noisy exhaust of marine explosion engines, in combination, a water-containing chamber, a passage for supplying said chamber from the water of flotation, an exhaust passage from the engine entering said chamber, and an exhaust delivery passage independent of the water supply passage and leading from the water-containing chamber above its water level. 85

2. In a device for preventing noisy exhaust of marine explosion engines, in combination, a water-containing chamber, a passage for supplying said chamber from the water of flotation, an exhaust passage from 90 the engine entering said chamber, a discharge passage from the water-jacket of the engine communicating with the water-containing chamber, and an exhaust delivery passage independent of the water supply passage and leading from the water-containing chamber above its water level. 95

In testimony whereof, I have hereunto subscribed my name this 5th day of August, 1908.

THOMAS B. DOOLITTLE.
